UNITED STATES PATENT OFFICE.

HENRY NEWTON, OF DARLEY, NEAR DERBY, ENGLAND.

TRENCH MORTAR AND THE LIKE.

Original application filed November 17, 1917, Serial No. 202,475, and in Great Britain March 22, 1916.
Divided and this application filed March 11, 1922. Serial No. 543,001.

(GRANTED UNDER THE PROVISIONS OF THE ACT OF MARCH 3, 1921, 41 STAT. L., 1313.)

- This invention relates to charges for trench mortars or other low pressure guns and has for its object to provide arrangements of propellant charges which will operate satisfactorily in smooth bore mortars and in which the quantity of propellant may be varied to suit varying ranges of target and which will also operate more satisfactorily in use under varying conditions.
- 10 The invention consists in a charge for trench mortars or other low pressure guns comprising a plurality of separate and distinct parts, one or more primary charges and one or more secondary charges, the primary charge or charges burning rapidly and thereby creating a temperature and pressure environment proper to ensure the complete combustion of the secondary charge or charges.
- 15 20 The invention also consists in a charge of the above character in which the primary charge or charges may be confined in a combustion chamber.

The invention further consists in a charge 25 of the above character in which the primary charge or charges may be carried in a combustion chamber provided upon the base of the projectile.

The invention still further consists in a 30 charge for trench mortars or other high or low pressure guns in which the combustion chamber carrying the primary charge is provided with ports for the emission of the propellant gases.

35 The invention also consists in other details and arrangements hereinafter described or indicated.

40 My invention will now be described with reference to the accompanying drawings, in which:—

Figure 1 shows one form of charge in accordance with the invention adapted to be used with a gun of the trench mortar type;

45 Figure 2 shows a modified form of charge;

Figure 3 shows a further modification of the invention as applied to a projectile provided with wings or vanes.

50 In carrying my invention into effect in one convenient manner as illustrated in Figure 1, I provide upon the base of the projectile *a* a cylindrical or other extension *b* having gas emission ports *b'* provided therein and adapted to receive the primary charge

or charges *c* which may be ballistite or other similar explosive contained within the cartridge container *d*, a secondary charge *e* being provided surrounding the extension *b* in the manner shown. If desired, the secondary charge *e* may comprise two or more parts, so that it may be varied as may be required for variation in range, and the said secondary charges may further be of any suitable form.

55 If necessary or desirable, both primary and secondary charges may be located in the breech or base chamber of the gun instead of being placed at the base of the projectile.

60 In the form shown, wherein the projectile carries its own propellant charge, the mortar or like gun is provided with the usual striker pin fixed at the bottom of the barrel or, if desirable, the cartridges may be provided with a self-contained striker, in which case a flat topped stud or anvil only is fixed in the mortar, whereby the primer *f* attached to the base of the projectile is adapted to be fired 70 when the projectile falls to the lower end of the barrel under the action of gravity.

75 Again, the shell may carry a trip mechanism preferably adjustable so that it might operate the igniting cartridges at predetermined points, giving a shorter or longer stroke for the shell, as may be required for range.

80 If desired, the charge may comprise a secondary slow burning charge or charges, such as cordite, and a primary quick burning charge or charges, such as gun-cotton yarn.

85 In the modification shown in Figure 2, the extension *b* containing the primary charge may be provided with ports *g* located at a part adjacent the point of ignition of the propellant whereby the pressure and temperature of the propellant gases may be increased.

90 I am well aware of the common use of a primer as a means of igniting a large charge from a percussion cap, and I make no claim herein to such primers, which are merely a means of applying a flame to the surface of the charge.

100 Figure 3 shows an arrangement whereby the invention is applied to a projectile provided with blades or vanes. In this case the propellant charge comprises secondary charges of slow burning explosive *j*, such as cordite, and primary charges of quick burn-

ing explosive *j*', such as gun-cotton yarn, each of these charges being sewn or sealed up in a separate muslin or cellulose or other bag; it being obvious, however, that both the primary charge or charges and the secondary charge or charges may be inserted in a single bag, the charges being located between the blades or vanes *l* having holes or slots *n* provided on their outer edges, as shown, through which wire or other binding material may be passed for the purpose of securing the bags to the projectile, it being understood that the bags containing the charges may be formed of any suitable material, such as silk, celluloid or the like.

Charges according to my invention comprising one or more primary and one or more secondary charges may be applied with advantage to high pressure guns as well as to low pressure guns, and by such means erosion will be reduced to a minimum or prevented to a great extent, while at the same time the ranges obtainable will be considerably increased.

By the use of such charges in long range guns the pressure can be raised in the fixed chamber of the gun to a predetermined extent in a predetermined time, no matter what the size of the secondary charge may be, this being a matter of great importance, for example, in the case of howitzers in which varying charges are used in the same capacity chamber, so that by my invention, even with such varying charges, a definite and uniform rate of burning of the charge may be obtained.

It will be understood that the invention is not to be confined to use with any particular form of gun or mortar. Also that the location of the primary and secondary charges may be varied relatively to one another as both charges may, if necessary, be located within the base of the gun and, furthermore, such charges may comprise either

slow burning or quick burning propellants 45 as may be found necessary, such modifications coming within the scope of the invention.

Having now described my invention, what I claim as new and desire to secure by Letters Patent is:—

1. A charge for trench mortars and other low pressure guns comprising a metal container having gas apertures, a primary charge within said container, and a secondary charge spaced from said primary charge by said container. 55

2. A projectile for trench mortars and other low pressure guns comprising a body portion containing explosive, a metal container at the rear end of said body portion having gas apertures, a primary charge in said container, and a secondary charge spaced from said primary charge by said container. 60

3. A projectile for trench mortars and other low pressure guns comprising a body portion containing explosive, tail vanes secured upon the end of said body portion, and a propellant charge located and retained 70 between said vanes. 65

4. A projectile for trench mortars and other low pressure guns comprising a body portion containing explosive, tail vanes secured upon the end of said body portion, 75 and a propellant charge formed in a plurality of distinct parts located and retained between said vanes.

5. A projectile for trench mortars and other low pressure guns comprising a body portion, tail vanes secured thereon, a primary charge adapted to burn rapidly, a secondary slower burning charge located and retained in proximity to said primary charge between said tail vanes. 80 85

In testimony whereof I have signed my name to this specification.

HENRY NEWTON.
